UNITED STATES PATENT OFFICE.

DAVID L. WENRICK, OF HARRISBURG, PENNSYLVANIA.

SASH-FASTENER.

1,312,933.

Specification of Letters Patent. Patented Aug. 12, 1919.

Application filed April 4, 1919. Serial No. 287,408.

To all whom it may concern:

Be it known that I, DAVID L. WENRICK, a citizen of the United States, residing at Harrisburg, in the county of Dauphin and 5 State of Pennsylvania, have invented a new and useful Sash-Fastener, of which the following is a specification.

This invention relates to improvements in sash fasteners for windows, the object of 10 the invention being to provide an improved fastener that is adapted to lock the sashes at any position so as to permit the upper and lower sashes to be raised and lowered to any desired height and at the same time 15 effectively prevent the sashes from being further raised or lowered from the outside.

A further object of the invention is to provide a sash fastener that will securely 20 lock the sashes at any desired point without forcing the upper and lower sashes apart at the meeting rail, and which will effectively prevent rattling of the sashes.

With the foregoing and other objects in view, which will appear as the description 25 proceeds, the invention consists in the novel features of construction and combination of parts which will be more fully described hereinafter and particularly pointed out in the claims.

30 In the drawings accompanying and forming part of this specification,

Figure 1 is a sectional view taken on the line 1—1 of Fig. 2, showing a portion of a window sash having my improved fastener 35 applied thereto; and

Fig. 2 is a plan view thereof, the side bar of the upper sash frame being shown in section.

The same characters of reference designate 40 the same parts in the different figures of the drawings.

Referring to the drawings, 2 designates the side bar of the upper sash and 3 the upper cross plate of the lower sash. The 45 fastener in the present instance comprises a base plate 4 provided with suitable countersunk openings for the passage of screws 5 for securing the plate to the upper cross plate 3 of the lower sash. The base plate 4 is provided at its upper side, approximately centrally thereof, with a raised circular boss 6 and at the under side thereof with a circular depression 7 concentric with said boss. The base plate is further provided with an opening 8 passing through 55 said boss preferably adjacent to one side of

the depression 7. Pivots mounted on said base plate is a brace member or link 9, provided at one end thereof with an enlarged circular opening 10 adapted to receive a projection or boss 11 extending from a lever 12, said lever having a shoulder 13 around said boss adapted to seat on the upper side of the link member 9. An opening 14 passes through the lever eccentrically 60 located with relation to the boss 11 and adapted to register with the opening 8 in the base plate for the reception of a rivet 15 for pivotally securing the lever and link on the base plate, as clearly shown in Fig. 70

1. The opposite end of the link is of L-shaped formation and is adapted to receive an L-shaped bracket 16 that is provided with a projecting perforated ear 17, a rivet 18 passing through the ear 17 and through 75 a perforation in the link member for pivotally securing the bracket to the link. To prevent marring of the sash frame, I provide an efficient gripping member 19, secured to the bracket and formed of rubber 80 or other flexible material, glued or otherwise secured to the bracket 16 at the inner sides thereof, said gripping member 19 being preferably shaped at its outer side to conform to the shape of the side bar 2, as 85 shown in Fig. 2. By this construction, the link may be pulled bodily away from the sash so as to release the same for permitting the sashes to be moved up or down without interference with each other. 90

When it is desired to lock the window, the lever is thrown over toward the right, the eccentric action of the boss 11 forcing the link outwardly toward the side bar 2 and thus clamping the bracket 16 against the 95 side bar. It will thus be seen that the locking pressure exerted by the link is in the direction of the width of the window, so that such pressure tends to force the sash frames against the side frames of the window, and does not force the sashes apart, which is of great advantage, since such forcing apart of the sashes causes considerable strain on the comparatively slender strip at the outside of the upper sash. In fact, in the use of this device if such strip were entirely removed the upper sash would still be held securely in place against the side bar of the window frame. It is to be noted that the opening 7 in the link 9 is not exactly in line with the 100 L-shaped end of the link. This peculiar formation has the effect of bringing the pres- 105 110

sure of the lever always against the rivet rather than against the opening in the link and renders the operation of the lever very easy.

- 5 While I have described in detail the structure herein illustrated, it is to be understood that I do not thereby limit my invention to the precise features of construction shown, as I am aware that many mechanical changes 10 may be made without departing from the spirit and scope of the invention as set forth in the appended claims.

Having thus described my invention, what I claim is:

- 15 1. A device of the class described, comprising a base plate, a link pivotally secured thereto, and a lever pivotally secured to said plate and link and adapted to exert pressure on the link in the direction of the length of

20 2. A device of the class described, comprising a base plate, a link seated on said base plate, and a lever seated on said link, said base plate, link and lever being connected together at a single point and said lever and link being eccentrically connected whereby the lever will be adapted to exert pressure on the link in the direction of the length of the link.

25 3. A device of the class described, comprising a base plate, a link pivotally secured thereto, a lever pivotally secured to said plate and link and adapted to exert pressure on the link in the direction of the length of said link, and a gripping member carried at the end of the link opposite its pivotal connection with the lever.

4. A device of the class described, comprising a base plate, a link having an enlarged opening therein, and a lever having

a projection adapted to fit within said opening, said base plate, link and lever being pivotally connected together eccentrically of said projection and opening whereby rotation of the lever will cause movement of the 45 link in the direction of its length.

5. A device of the class described, comprising a base plate, a link pivotally secured at one end thereof to the base plate, and a lever pivotally secured to the link and base 50 plate and adapted to exert pressure on the link in the direction of the length of the link, said link being formed at its opposite end with an angular portion out of alignment with said pivotal connection, and an angular bracket pivotally secured to said link and adapted to be seated within said angular portion.

6. In a device of the class described, the combination with a pair of companion window sashes, of a base plate adapted to be secured to the frame of one of the sashes, a link seated on said base plate and adapted to engage the frame of the other sash, said link having a circular opening formed 65 therein, and a lever having an annular projection adapted to fit said opening, said link and lever being pivotally secured to said base plate at a single point eccentrically of said projection, whereby rotation of the 70 lever around its pivot will cause said link to engage and disengage the frame of the sash.

In testimony that I claim the foregoing as my own I have hereto affixed my signature 75 in the presence of two witnesses.

DAVID L. WENRICK.
